RETURN BEND FOR CRACKING STILLS

Charles E. Ard, Birmingham, Ala., assignor to
Fred C. Fantz, Webster Groves, Mo.

Application January 25, 1933, Serial No. 653,394

1 Claim. (Cl. 285—20)

My invention relates more particularly to that class of return bends which are used to connect adjacent tubes in the nest coil banks of a cracking plant as used in an oil refinery.

5 It is well known that the constant tendency in the industry is towards higher pressure and higher temperatures. The inevitable result of this tendency is that the construction of the return bend has been constantly increased in 10 weight, owing to the necessity of providing an extremely rugged construction to withstand the increased pressures and temperatures which in some instances in practice have run up to as 15 high as 15,000 lbs. pressure and 1400 degrees temperature.

A further condition directly due to this demand for increased temperature and pressure is the requirement for the provision of demountable tubes instead of having them rolled into 20 the housing or header as was formerly the custom.

In this type of construction it has been customary to provide a housing having upwardly 25 extending side walls in which were mounted toggles carrying set screws which were adapted to exert pressure against the return bend and to force it into tight engagement with the ends of the tubes. A very considerable amount of force had to be exerted and the result was that 30 there was a tendency to pull the end of the tube off by the tightening of the set screw.

My invention has for its principal object to improve the joint between the return bend and the tube so that the only force exerted which 35 would tend to pull the end of the tube off is that by the pressure of the fluid inside of the tubes and return bend.

A further object is to provide a construction in which the force exerted by the tightening 40 of the toggle will be used to compress or seal the joint which is in compression between the housing and the U bend. As a consequence it is possible with this invention to provide a much lighter form of construction than can possibly 5 be used where the other type of joint is employed.

By means of accomplishing the foregoing objects may be more readily understood by having reference to the accompanying drawing which is hereto annexed and is a part of the specification in which—

Fig. 1 is a side elevation partly in section of my improvement;

Fig. 2 is a top or plan view of the same; and

Fig. 3 is a detail view.

Similar reference numerals refer to similar parts throughout the entire description.

As shown in the drawing, I have provided a conventional return or U bend 1 which is adapted to connect a pair of adjacent still tubes 2 and 3. These tubes are provided with upset portions 4 adjacent their ends. Inasmuch as the construction of the joint for each tube is identical, I shall only describe a single tube and the manner of making the connection between it and the U bend 1. In the upset portions 4 I form a circumferential groove 5. Inasmuch as this groove 5 is in the upset portion 4 of the tube, it can be made with perfect safety and without any danger of the tube giving way.

The housing in which the tube and return bend are mounted comprises annular portions 6 and 7 which are connected by a web 8 which serves to hold the tubes in alignment when the U bend 1 is removed.

The annular portions 6 and 7 are provided with upwardly extending side walls which are arcuate in cross section. These side walls are provided with internal grooves or slots 10 in which are mounted the toggles 11. These toggles carry set screws 12, the inner ends 13 of which are adapted to engage abutments 14 formed on the external wall of the return bend 1.

In the groove 5 I mount a ring which is split on one side in the same manner that a piston ring is split. This ring as clearly seen in the drawing is V shaped in cross section. The upper surface 15 of which is fitted to and coincides with a beveled portion 16 formed on the face of the return bend 1. The lower inclined surface 18 of the ring is engaged by a coinciding surface 17 formed on the inner wall of the annular portion 6 of the housing.

The assembly of the device is as follows:—

The tubes 2 and 3 are passed through the openings in the annular members 6 and 7 of the housing and a ring is snapped into each groove 5 formed in the upper portion 4 of the tubes. The return bend is placed over the ends of the tubes and the beveled portion 16 is brought into contact with the inclined surface 15 of the ring. The toggles 11 are then placed in position the set screws 12 are tightened and this exerts a force which tends to compress the ring and will produce a very satisfactory joint.

It will be obvious to persons skilled in the art, that with this construction, the only thing that the toggle does, is to compress the ring and there is no tendency to pull the end of the tube

off. The only pressure which tends to produce such a result would be produced by the fluid on the interior of the tube on return bend.

It will be also apparent that by this construction and in view of the foregoing statement that the entire construction can be very much lighter than is the case under normal circumstances for it will be seen that there is no joint between the tube and the U bend or between the tube and the annular member that has to be sealed. The only joint which necessarily must be sealed is that between the U bend and the tube itself and this as stated, is sealed by compression.

15 Although I have described a groove formed in the tube, it may be found desirable in practice to provide an upset shoulder on the tube and I do not desire to be understood as limiting myself to the precise structure shown in this case.

20 Having described my invention what I regard as new and desire to secure by Letters Patent is—

In a refinery apparatus, a conventional return bend adapted to connect a pair of upset still tubes to provide a continuous passageway therethrough, a housing comprising annular portions adapted to encircle the end of said tubes, upwardly extending side walls on said annular portions, toggles mounted in said side walls, set screws in said toggles, the inner ends of which contact abutments formed on said return bend, there being peripheral grooves in the upset portion of said tubes, a resilient split ring mounted in each groove, said ring being V shaped in cross section, annular beveled surfaces on the face of the return bend which are fitted to and coincide with the upper surfaces of said rings, corresponding beveled surfaces on the inner walls of said annular portions which contact the lower surfaces of said rings, whereby the tightening of said set screws operates to compress said rings and seal the joint between the return bend and the tubes.
